UNITED STATES PATENT OFFICE.

ERNEST M. LE BLANC, OF NEW ORLEANS, LOUISIANA.

GARMENT-DISPLAY STAND.

Application filed November 15, 1921. Serial No. 515,246.

To all whom it may concern:

Be it known that ERNEST M. LE BLANC, a citizen of the United States of America, residing at New Orleans, in the parish of 5 Orleans and State of Louisiana, has invented new and useful Improvements in Garment-Display Stands, of which the following is a specification.

The object of the invention is to provide 10 an efficient display stand or rack for garments, designed to hold the supported garment in the most favorable condition to indicate the shape, set and style thereof and as near as possible to demonstrate the appearance 15 thereof when actually worn; and with this object in view the invention consists in a construction and combination of parts of which a preferred embodiment is shown in the accompanying drawings, wherein:—

20 Figure 1 is a view of the stand or rack adapted for supporting trousers.

Figure 2 is a detail view of the upright used in connection therewith.

Figure 3 is a similar view of the slide and 25 attached locking means.

Figure 4 is a similar view of one of the shoes carried by the supporting arms.

Figure 5 is a standard employed in connection with a suit or skirt supporting stand.

30 Figure 6 is a detail view of the foot of one of the standards.

Figure 7 is a view of the stand or rack arranged for supporting a skirt or ladies' suit.

35 Figures 8 and 9 are detail views of the forming frames employed respectively in connection with the stand as arranged in Figures 7 and 1.

Essentially the device consists of supporting 40 means carrying an upright which in the construction illustrated in Figure 1 is shown at 10, upwardly divergent supporting arms 11, braces 12 hingedly connected, as at 13 to the supporting arms and also hingedly 45 connected, as at 14 to a slide or sleeve 15 mounted upon the upright and shown in detail in Figure 3, and forming frames 16 which are carried by the upper ends of the supporting arms 11 and which in the construction 50 shown in Figure 1 are connected with said supporting arms by means of shoes 17 shown in detail in Figure 4.

The forming frames are preferably constructed of wire and embody front and rear members 16^a and 16^b which are of plural ply form and are bulged or arched with their

ends arranged in adjacent or slightly overlapping relation according to the adjustment of the supporting arms 11 and the girth of the garment which is supported thereby, to maintain the garment in a proper position to show the shape thereof as when worn. The construction illustrated in Figure 1 is particularly designed for displaying trousers and the shoes 17 are provided with reduced or cut in portions 17^a at their upper ends to receive the waist band of the garment while the front and rear portions thereof are held in proper position by the forming frames, and the support is represented by the standards 18 which support the arms 11 and upright 10 and which are provided at their lower ends with feet 19 preferably movable to positions in alignment with the standards to permit of extending the latter through the legs of the trousers. The feet as shown are hinged at 20 to the lower ends of the standards and are provided with catches 21 for engaging studs 22.

In order to hold the expanding frame represented by the supported arms Figure 1 and forming frames carried thereby at the desired adjustment to properly support the garment, the slide or sleeve 15 which is 45 slidably mounted upon the upright 10 is provided with a spring 23 having a tooth 24 for engagement with a selected seat 25 in a plate 26 inset in the upright as shown in detail in Figure 2.

In the form of the device which is illustrated in Figure 7 the upright 10^a corresponding with that described in relation to the form shown in Figure 1 carries the expanding frame consisting of the supporting arms 11^a, braces 12^a, slide or sleeve 15^a and locking device 23^a, together with complementary forming frames 27 shown in detail in Figure 8 and having the front and rear members 27^a and 27^b of which the latter are adapted to support the shoulder portions of a garment waist indicated in dotted lines at 28. This form of the stand also preferably embodies a second expanding frame having the arms 11^b, braces 12^b, slide or sleeve 15^b and locking means 23^b with terminal shoes 17^b on the extremities of said supporting arms, as a means of holding the skirt portion of the garment indicated in dotted lines at 29 in the proper position, the shoes 17^b serving as 110 a means of engaging the waist band of the skirt just as the shoes 17 serve to engage the

waist band of trousers or like garment. The upright 10^a of the form shown in Figure 7 is supported by a standard 18^a which in the construction illustrated is formed as a part of the said upright and is provided with a suitable foot 19^a.

Having described the invention, what is claimed as new and useful is:—

1. A garment display stand having an upright, upwardly divergent arms hingedly connected at their lower ends to said upright, a sleeve slidably mounted on said upright and provided with means for adjustment longitudinally of the upright, brace members hingedly connected at their upper ends with the sleeves and depending therefrom in divergent relation and having hinged connections at their lower ends with the upwardly divergent arms at intermediate points of the latter, and garment forms carried by the upper extremities of

said arms for arrangement within a garment in supporting relation thereto.

2. A garment display stand having an upright, upwardly divergent arms hingedly connected at their lower extremity to the upright, adjustable means for uniformly varying the angular relation between said arms and said uprights, and garment forms consisting of independent frames having shoes mounted upon the upper extremities of the arms and provided with forwardly and rearwardly directed wings, said shoes being channeled shaped and disposed in straddling relation with the free extremities of said arms and having reduced or cut in portions at their upper ends to receive the waistband of a garment.

In testimony whereof he affixes his signature.

ERNEST M. LE BLANC.
